(57) **CLAIM**

The ornamental design for a “luffa holding device” as shown and described.

DESCRIPTION

FIG. 1 is a top, front, and left-side perspective view of a first embodiment of my new design for a luffa holding device. FIG. 2 is a top, rear, and left-side perspective view of the luffa holding device of FIG. 1.

FIG. 3 is a front view of the luffa holding device of FIG. 1. FIG. 4 is a rear view of the luffa holding device of FIG. 1. FIG. 5 is a top view of the luffa holding device of FIG. 1. FIG. 6 is a bottom view of the luffa holding device of FIG. 1.

FIG. 7 is a left-side view of the luffa holding device of FIG. 1.

FIG. 8 is a right-side view of the luffa holding device of FIG. 1.

FIG. 9 is a cross-section view taken along line 9-9 of the luffa holding device of FIG. 3.

FIG. 10 is a top, front, and left-side perspective view of a second embodiment of my new design for a luffa holding device.

FIG. 11 is a top, rear, and left-side perspective view of the luffa holding device of FIG. 10.

FIG. 12 is a front view of the luffa holding device of FIG. 10.

FIG. 13 is a rear view of the luffa holding device of FIG. 10.

FIG. 14 is a top view of the luffa holding device of FIG. 10.

FIG. 15 is a bottom view of the luffa holding device of FIG. 10.

FIG. 16 is a left-side view of the luffa holding device of FIG. 10.

FIG. 17 is a right-side view of the luffa holding device of FIG. 10.

FIG. 18 is a bottom, front, and right-side perspective view of a third embodiment of my new design for a luffa holding device, the remaining views being the same as the foregoing embodiments of FIGS. 1-9, except for the release tab and gripping feature differences.

FIG. 19 is a cross-section view taken along line 19-19 of the luffa holding device of FIG. 18.

(Continued)

FIG. 20 is a bottom, front, and right-side perspective view of a fourth embodiment of my new design for a luffa holding device, the remaining views being the same as the foregoing embodiment of FIGS. 1-9, except for the release tab and gripping feature differences.

FIG. 21 is a cross-section view taken along line 21-21 of the luffa holding device of FIG. 20.

FIG. 22 is a bottom, front, and right-side perspective view of a fifth embodiment of my new design for a luffa holding device, the remaining views being the same as the foregoing embodiment of FIGS. 1-9, except for the release tab and gripping feature differences.

FIG. 23 is a cross-section view taken along line 23-23 of the luffa holding device of FIGS. 22.

The broken lines shown in FIGS. 1-9 depict portions of the luffa holding device that form no part of the claimed design.
